AUTOMATIC MINE TRAP DOOR

Earnest L. Tucker, Coalburg, W. Va.

Application October 17, 1938, Serial No. 235,502

3 Claims. (Cl. 20—16)

The invention relates to an automatically closing gravity acting door and more especially to trap doors for mines or the like.

The primary object of the invention is the provision of a door of this character, wherein through the use of an adjustable hinge disposed at an incline to the vertical in association with the door, the latter will be automatically closed and in this closed position by reason of the novel make-up of the door, the doorway or entrance to a mine will be rendered practically air-tight and the closing of the door is had through gravity thus eliminating manual labor for the closing of such door.

Another object of the invention is the provision of a door of this character, wherein the construction thereof is novel and is susceptible of adjustment to assume the proper working thereof for the automatic closing of the same and also to properly fit a doorway for the closing thereof.

A further object of the invention is the provision of a door of this character, which is comparatively simple in its construction, thoroughly reliable and efficient in operation, automatically operating in one direction for self-closing action, strong, durable, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation partly in vertical section showing the door constructed in accordance with the invention.

Figure 2 is a horizontal sectional view thereof showing by full lines the door in a closed position and by dotted lines the said door swung to reverse open positions.

Figure 3 is a sectional view on the line 3—3 of Figure 1 looking in the direction of the arrows.

Figure 4 is a sectional view on the line 4—4 of Figure 1.

Figure 5 is a sectional view on the line 5—5 of Figure 1 looking in the direction of the arrows.

Similar reference characters indicate corresponding parts throughout the several views in the drawings.

Referring to the drawings in detail, A designates generally the gravity acting self-closing door and B a doorway creating an entrance or opening to a mine or the like. This doorway B

involves in association therewith a sill area having boards 10 and a header involving roofing boards 11, respectively, while 12 and 13 denote the reversely inclined upstanding side members of the door frame, being extended upwardly from the sill line to the header or roofing line, respectively.

Arranged at the foundation area is a track involving rails, portions thereof being indicated at 14 for a mine car (not shown), which is adapted in its travel to pass into and without the mine through the doorway B as is customary, the track being counterseated to have the treads of the rails flush with the upper surface of the sill area as will be apparent from Figure 1 of the drawings. The arrangement of the track is such as to minimize crevices at the sill or foundation line to assure a closing of the door A to avoid leakage of air at such point.

The door A comprises a frame 15 supporting outwardly bulged major and flat minor facings 16 and 17, respectively, at opposite sides, these being made fast and made from continuous metal sheeting bolted or otherwise secured to the frame 15 while disposed at the merger of the facing 16 with the facing 17 and outside the sheeting constituting the same is a pivot being inclined to the vertical and includes upper and lower relatively adjustable substantially U-shaped parts 18 and 19, respectively, the part 18 being inverted with relation to the part 19 and is telescopically interfitted with the latter. Transverse fasteners 20 are passed through holes 21 therefor provided in said parts 18 and 19 and also through the door A, these fasteners 20 being selectively fitted in the holes 21 to allow of adjustment of the parts 18 and 19 with respect to each other according to the required extent of the pivot in association with the door. The outer closed ends of the parts 18 and 19 are formed with pivot lugs 22 turnable in pivot bearings 23 and 24, respectively, the latter being formed with a shift plate 25 movably fitted with the sill of the door frame and slidably held by fasteners 26 while coacting with this plate 25 is an adjusting device 27 to regulate the throw of the bearing 24 for altering the inclination of the pivot for the door. The bearing 23 is adjustably held at the header or roofing 11.

Secured to the bottom edge and opposite end edges of the door A are wiper acting flexible closure strips 28 which extend throughout said edges, being fastened in place in any suitable manner, while working in a guideway 29 in the upper edge of said door A is a self-adjusting carrier 30 provided with wiper acting flexible closure stripping 55

31. This carrier is supported for rocking movement on a transversely arranged pivot 32 fitting the part 18 and passed horizontally through the sheeting of the door A. This carrier accommodates the stripping 31 to the roof or header of the door frame B and due to the swing of the door A the said carrier 30 coacts with a cam 33 on which rides a roller 34 fitting said carrier so that when the door A through gravity action automatically closes there will be no interference of the stripping 31 with the door frame B while the flexible strips 28 and 31 will effect a practically air-tight seal marginally of the door A by contact with the door frame B when the said door A has become completely closed.

The angular disposition of the pivot for the door A to the vertical assures a positive gravity action of the said door in a closing direction when the latter is swung to either side of its pivotal axis to an open position.

Arranged at opposite sides and at the proper points with relation to the door frame B are posts 25, these being vertically disposed in the path of movement of the door A and function as stops for limiting the opening movements of said door to either side of the doorway.

Built with the door frame B is an auxiliary door frame 36 with which is associated a swinging door 37. The hinge 38 for the door 37 is inclined laterally to the vertical with relation to the main door frame so that the said door 37 when manually swung open through gravity will swing to closing position. This door affords an entrance for workmen and also an exit and thus in this manner eliminating the necessity of the opening of the door A which overrides the trackage constituted by the rails 14. The bulged major portions 16 of this door is so disposed with respect to the trackage that the car traveling thereon on contact with the bulged major portions will force the door to an open position for the free passage of the said car through the door frame B into or from the mine or the like while the pivotal mounting of this door A assures the automatic closing of the door through gravity action. When the door A is in a closed position in the door frame, leakage of air therethrough is avoided, this being effected by the flexible closure strips 28 and 31, respectively, through wiping contact with the door frame.

It is preferable to have the members 12 and 13 of the door frame B protected by metal sheathing 39 fastened thereto as at 40.

The door A and the mounting thereof is susceptible for uses other than specifically referred to and will automatically operate through gravity for the closing thereof.

The flat facings 41 are separably bolted in place and this minor portion of the door by al-

teration of its framing can be dispensed with where the haulage way is narrow and thus accommodating the door to a door frame in conformity with such narrow haulage way.

The door, by reason of its construction, is possessed of maximum strength and there is no liability of the car on the trackage getting caught with the door to interfere with the operation of either of the same.

The door frame 36 at the hinged edge of the door 37 is equipped with a stop 41 limiting the opening movement of said door.

What is claimed is:

1. The combination of a door frame, a door movable through said door frame from closed to opened position, a pivot inclined to the vertical within said door frame and movably supporting the door for gravitation thereof to closed position, means associated with said pivot for varying the disposition thereof for increasing or decreasing gravity action of the door, flexible closures carried at the bottom and side edges of the door, and a self-adjusting flexible closure member interfitted with the door at its top edge and swingingly supported.

2. The combination of a door frame, a door movable through said door frame from closed to opened position, a pivot inclined to the vertical within said door frame and movably supporting the door for gravitation thereof to closed position, means associated with said pivot for varying the disposition thereof for increasing or decreasing gravity action of the door, flexible closures carried at the bottom and side edges of the door, a self-adjusting flexible closure member interfitted with the door at its top edge and swingingly supported, a cam fixedly arranged with the door frame, and means on the closure member at the top edge of the door and coactive with said cam for regulating movement to said closure member.

3. The combination of a door frame, a door movable through said door frame from closed to opened position, a pivot inclined to the vertical within said door frame and movably supporting the door for gravitation thereof to closed position, means associated with said pivot for varying the disposition thereof for increasing or decreasing gravity action of the door, flexible closures carried at the bottom and side edges of the door, a self-adjusting flexible closure member interfitted with the door at its top edge and swingingly supported, a cam fixedly arranged with the door frame, means on the closure member at the top edge of the door and coactive with said cam for regulating movement to said closure member, and an extensive section for said door at one side of the pivot.

EARNEST L. TUCKER.
